RAILWAY TRAFFIC CONTROLLING
APPARATUS

Herman G. Blosser, Pittsburgh, and Charles W. Sailor, Forest Hills, Pa., assignors to The Union Switch & Signal Company, Swissvale, Pa., a corporation of Pennsylvania

Application June 3, 1933, Serial No. 674,200

14 Claims. (Cl. 246—130)

Our invention relates to railway traffic controlling apparatus, and more specifically to apparatus for clearing out highway crossing cut sections, operating detector locking track circuits, as well as for clearing out detector track sections generally, in signaling systems employing coded track circuit current for the control of wayside and cab signals.

One feature of our invention is the provision of apparatus of the above character which will not cause improper operation of cab or wayside signals. Another feature is the provision of complete broken down insulated rail joint protection, without requiring numerous control relays and using a minimum number of control line wires per track circuit.

We will describe one form of track circuit clearing apparatus embodying our invention, and will then point out the novel features thereof in claims.

The accompanying drawing is a diagrammatic view of a stretch of railway track with the associated apparatus embodying our invention as applied to the clearing out of highway crossing cut sections upon the passage of a train.

Referring to the drawing, the block section D—G, in which traffic normally moves from left to right in the direction of the arrow, is divided into cut sections D—E, E—F, and F—G for the purpose of controlling highway crossing signals XS² and XS³ at locations E and F. Each of the above sections is provided with a track transformer T and a code-following track relay TR. Adjacent track circuits have staggered instantaneous polarities, and the track relays are of the two-element type having a local winding 1 and a control winding 2 so that reverse torque, tending to open the front contacts of these relays, will be developed should a breakdown of the insulated rail joints occur.

For simplicity, the continuously operating code transmitters CT and CT⁴ at locations D and G, respectively, are shown as supplying track circuit current of but two code frequencies, namely, a current of 180 interruptions per minute over the periodically closed contact 180, and current of 80 interruptions per minute over the periodically closed contact 80, for the control of wayside and cab signals. In practice, additional code frequencies, selected in accordance with traffic conditions in advance, will normally be used to provide control for multiple aspect wayside and cab signals. One form of code transmitter, and one arrangement of apparatus for selecting the code to be applied to a track section in accordance

with traffic conditions in advance, are shown and described in Letters Patent of the United States No. 1,773,472, granted to P. N. Bossart on August 19, 1930, and so these parts of the system are illustrated diagrammatically in the present case to simplify the disclosure.

When current of 180 code frequency flows in the rails of section D—E which is assumed to be unoccupied, relay TR¹ will operate in step with the code impulses, and the periodic closing of contacts 3—4 and 3—5 of this relay will cause direct current to be supplied alternately to one and then to the other half of the primary winding of decoding transformer DT, to induce an alternating voltage in the secondary winding. The circuit of the secondary winding of transformer DT is tuned to the 180 code frequency by reactor X¹ and condenser C¹, so that the slow releasing decoding relay DR, which is energized from the tuned circuit through a rectifier R¹, will remain picked up as long as section D—E is supplied with rail current of 180 code frequency. In a similar manner, the untuned decoding relay DR¹, which is energized through rectifier R², will remain picked up as long as section D—E is supplied with rail current of either 180 or 80 code frequency. If the code frequency is 180, front contacts 6—7 and 30—31 of relays DR and DR¹ will be closed, thereby causing lamp G of signal S to become energized. Signal S will therefore indicate "proceed". When the code frequency is 80, relay DR will be released, and relay DR¹ will be energized, so that lamp Y of signal S will be lighted over contacts 6—8 and 30—31 of relays DR and DR¹.

Upon shunting of relay TR¹ by a train, or prolonged interruption of the rail current, relay DR¹ will release due to the collapse of the secondary voltage in transformer DT, so that back contact 30—32 will close the circuit for lamp R of signal S, to provide a "stop" indication for following traffic.

Assuming again that section D—E is unoccupied and that relay TR¹ is following 180 code, contact 9—10 of relay TR¹ will close periodically, maintaining slow releasing relay K¹ energized, and contact 9—11 will also close periodically to maintain the slow releasing relay L¹ energized over front contact 12 of relay K¹. Relay L¹ controls the energization of crossing signals XS², and as long as relay L¹ is energized, these signals will remain inoperative by virtue of the open back contact 13. The relays K¹ and L¹ can be conveniently termed "decoding" relays because, as will appear from the description which follows,

these relays respond to code operation of the track relay TR¹.

We shall now explain the operation of the apparatus during the passage of a train from location D, through the various cut sections.

When the train enters section D—E, the operation of relay TR¹ will cease, opening contact 9—10 to release relay K¹, which in turn will release relay L¹, thus initiating operation of the crossing signals XS² at location E. When the train enters section E—F, relay TR² will release, releasing in turn relays K² and L² which are controlled in the same manner as relays K¹ and L¹ associated with section D—E. The release of relay K² will cause relay XR to release, due to the opening of front contact 14, thereby starting the operation of the crossing signals XS³ over back contact 16 of relay XR. The release of relay L², closing back contact 17, will result in energization of the auxiliary code transmitter ACT¹ which is provided for the purpose of supplying a clearing or detection code to track section D—E to clear out this section following the passage of the train into section E—F. This detection code must be of such character as not to cause response of the wayside signal S or of cab signals on a following locomotive which may have overrun location D; and, at the same time, this code must cause operation of relay TR¹ in such manner that both relays K¹ and L¹ will become picked up to stop the operation of the crossing signals XS².

One type of detection code which will accomplish the above results consists of a relatively short "on" period, followed by a relatively long "off" period, these periods being repeated successively. This type of code is employed in the apparatus which we have illustrated, and is supplied to transformer T¹, over the periodically operated contact 18 of transmitter ACT¹, wire 19, and back contact 20 of relay L². The transmitter illustrated diagrammatically at ACT¹ may comprise, for example, a motor element which, when energized, causes rotation of the contact operating cam to produce the short "on" and long "off" intervals of the code. Relay TR¹ will pick up during each "on" interval of the detection code, thus causing pick up of relay K¹ which is sufficiently slow releasing to bridge the "off" code intervals, during which relay L¹ will receive energy over contact 9—11 of relay TR¹ and contact 12 of relay K¹. Relay L¹ is sufficiently slow releasing to bridge the "on" code intervals, during which contact 9—11 remains open. It will be apparent, therefore, that the detection code will be effective to stop the operation of crossing signals XS², when no train is occupying section D—E. At the safe time, if the periodic frequency of the detection code is sufficiently far removed from the code frequency of the train governing code used for controlling cab and wayside signals, or if a suitable time ratio is established between the duration of the "on" and "off" detection code periods, there will be no response of wayside or locomotive decoding relays such as DR or DR¹. That is, the selection of a detection code frequency appreciably far removed from the train governing code frequency, or the suitable choice of the "on" and "off" time ratio will prevent the energization of decoding relays if the "on" period is of insufficient duration for pick up of these relays. If desired, a detection code comprising a relatively long "on" period, followed by a relatively short "off" period can also be used, provided the time elements of relays K¹, L¹ and DR

are suitably adjusted, or code frequency tuning of all wayside and locomotive decoding relays is used. Obviously, the detection code may be of any suitable character, provided it does not pick up relays DR or DR¹ and provided further that it operates relay TR¹ in such manner as to pick up relays K¹ and L¹.

When the train enters section F—G, relays TR³, K³ and L³ will all become deenergized, and the auxiliary code transmitter ACT² will become energized over back contact 21 of relay L³, and will furnish a detection code to section E—F, in the same manner that the detection code was furnished to section D—E, as previously described, to energize relay XR over front contacts 14 and 15 of relays K² and L², thereby stopping the operation of signals XS³. The picking up of relays K² and L² which follows the exit of the train from section E—F will cause transmitter ACT¹ to become inoperative due to opening of back contact 17 of relay L². It should be noted that the detection code which is supplied to section E—F will be relayed to section D—E, over the periodically operated contact 25 of relay TR² and front contact 20 of relay L², to maintain signals XS² in the inoperative condition.

When the train has entered the section starting at location G, relay TR⁴ will become deenergized, deenergizing relays DR⁴ and DR³, to cause signal S⁴ to indicate "stop" by virtue of the closing of back contacts 27 and 33. As soon as the train clears section F—G, train governing current of 80 code frequency, suitably selected by code selection apparatus which is not shown in the drawing, will be supplied by transmitter CT⁴ to transformer T³ thereby causing operation of relay TR³, which results in the energization of relays K³ and L³. The opening of back contact 21 of relay L³ will stop the operation of transmitter ACT², and track section E—F will then be supplied with current of 80 code frequency over the periodically operated contact 29 of relay TR³ and front contact 28 of relay L³. Relay TR² will follow the 80 code and will relay this code to track section D—E over contacts 25 and 20 of relays TR² and L², in the same manner that it previously relayed the detection code supplied by transmitter ACT². As soon as the block in advance of section F—G is cleared by the train, train governing current of 180 code frequency will be supplied to sections F—G, E—F, and D—E.

The presence of 180 code in the rails of section D—E will cause relay DR to pick up, through the periodic operation of relay TR¹, thereby causing signal S to indicate "proceed". It will now be apparent that when the block section D—G is unoccupied, all of its component cut sections will be receiving train governing current, relayed over the individual sections without the use of line wires, signal S will provide an indication in accordance with traffic conditions in advance, and the crossing signals XS² and XS³ will be deenergized.

Since section F—G is the last section in the block D—G, no special detection code such as that furnished by transmitters ACT¹ and ACT² is required in this section because any of the standard train governing codes furnished by transmitter CT⁴ can be used to clear relays K³ and L³. The "on" and "off" periods of the train governing codes being of substantially equal duration, relays K³ and L³ can have approximately the same release time, which is not necessarily true of relay groups K¹, L¹, and K², L², in which 75

groups the relays K¹ and K² should preferably have a substantially longer releasing time than relays L¹ and L², to insure satisfactory operation on a detection code having a short "on" and a long "off" period. If a detection code comprising a long "on" and a short "off" period is used, relays L¹ and L² will have a longer release interval than relays K¹ and K², but when the latter code is used, the increased release time of relays L¹ and L² may cause a slight delay in the starting of the crossing signals XS² and XS³.

To summarize, we have provided a track circuit clearing or train detecting system which requires a minimum number of control line wires, does not interfere with the operation of wayside or cab signals, and permits relaying of the train governing and detection codes to several rear sections without requiring additional line wires and apparatus for this purpose.

It will be apparent that our system can also be adapted for operation on coded direct current track circuits, by substituting direct current code-following track relays for the relays TR, and by eliminating the track transformers T and substituting a direct current source for the alternating current source BX—CX.

Should foreign current be present, or a mechanical defect develop in either of the code-following relays TR² or TR³, resulting in a failure of front contact 9—10 to open, the associated relay L² or L³ will become deenergized, removing train governing code from the rear track circuits up to the wayside signal location D, and causing signal S to indicate "stop". Similarly, should back contact 9—11 fail to open, both relays of group K², L², or K³, L³, will become deenergized, and the "stop" indication will again be displayed by signal S.

It will be noted that the circuit for the crossing signal control relay XR includes a front contact of each of relays L² and K². Although the use of front contact 15 of relay L² would alone be sufficient to check that relay TR² is following code, the inclusion of front contact 14 of relay K² makes possible a quicker response of relay XR for starting operation of the crossing signal, since relay K² is arranged to release before relay L².

Although we have herein shown and described only one form of apparatus embodying our invention, it is understood that various changes and modifications may be made therein within the scope of the appended claims without departing from the spirit and scope of our invention.

Having thus described our invention, what we claim is:

1. In combination, a first and a second section of railway track each normally supplied with a train governing code comprising rail current periodically varied at a frequency selected in accordance with traffic conditions in advance of said sections, means effective when said second section becomes occupied for discontinuing the supply of said train governing code to said first section and for supplying the rails of said first section with a detection code comprising periodically varied current having consecutive periodic variations of unequal duration, a code-following track relay for said first section capable of following either of said two codes, a slow acting relay controlled by said track relay in such manner as to become energized when the track relay is following either of said two codes and to become deenergized when the
2. In combination, a first and a second section of railway track each normally supplied with a train governing code comprising rail current periodically varied at a frequency selected in accordance with traffic conditions in advance of said sections, means effective when said second section becomes occupied for discontinuing the supply of said train governing code to said first section and for supplying the rails of said first section with a detection code comprising periodically varied current having consecutive periodic variations of unequal duration, a code-following track relay for said first section capable of following either of said two codes, a slow acting relay controlled by said track relay in such manner as to become energized when the track relay is following either of said two codes and to become deenergized when the
3. In combination, a first and a second section of railway track, means for supplying to the rails of said second section a train governing code comprising current periodically varied at a frequency selected in accordance with traffic conditions in advance, a first code-following track relay for said second section capable of following said train governing code, a first control relay which becomes energized when said first track relay is following said train governing code and which becomes deenergized when said first track relay is shunted, a source of detection code comprising periodically varied current having consecutive periodic variations of unequal duration, means including a back contact of said control relay for rendering said source effective for supplying said detection code to the rails of said first section, a second code-following track relay for said first section capable of following either of said two codes, a second control relay which is energized when said second track relay is following either of said two codes and which becomes deenergized when said second track relay is shunted, a signal controlled by said second control relay for indicating the occupancy of said first section, and means including a front contact of said first control relay effective when said first track relay is following said train governing code for relaying the train governing code from said second section to the rails of said first section.
4. In combination, a section of railway track normally supplied with a train governing code comprising rail current periodically varied at a frequency selected in accordance with traffic conditions in advance of the section, means for at times discontinuing the supply of said train governing code and for supplying the rails of said section with a detection code comprising

track relay is shunted, an indicator controlled by said slow acting relay for indicating the occupancy of said first section, and a signal for governing traffic entering said first section controlled by said track relay and responsive to operation of the track relay on said train governing code but not said detection code.

2. In combination, a first and a second section of railway track each normally supplied with a train governing code comprising rail current periodically varied at a frequency selected in accordance with traffic conditions in advance of said sections, means effective when said second section becomes occupied for discontinuing the supply of said train governing code to said first section and for supplying the rails of said first section with a detection code comprising periodically varied current having consecutive periodic variations of unequal duration, a code-following track relay for said first section capable of following either of said two codes, a slow acting relay controlled by said track relay in such manner as to become energized when the track relay is following either of said two codes and to become deenergized when the track relay is shunted, an indicator controlled by said slow acting relay for indicating the occupancy of said first section, a signal for governing traffic entering said first section controlled by said track relay and responsive to operation of the track relay on said train governing code but not said detection code, and means effective when both said sections become unoccupied for discontinuing the supply of said detection code and restoring the supply of said train governing code.

3. In combination, a first and a second section of railway track, means for supplying to the rails of said second section a train governing code comprising current periodically varied at a frequency selected in accordance with traffic conditions in advance, a first code-following track relay for said second section capable of following said train governing code, a first control relay which becomes energized when said first track relay is following said train governing code and which becomes deenergized when said first track relay is shunted, a source of detection code comprising periodically varied current having consecutive periodic variations of unequal duration, means including a back contact of said control relay for rendering said source effective for supplying said detection code to the rails of said first section, a second code-following track relay for said first section capable of following either of said two codes, a second control relay which is energized when said second track relay is following either of said two codes and which becomes deenergized when said second track relay is shunted, a signal controlled by said second control relay for indicating the occupancy of said first section, and means including a front contact of said first control relay effective when said first track relay is following said train governing code for relaying the train governing code from said second section to the rails of said first section.

4. In combination, a section of railway track normally supplied with a train governing code comprising rail current periodically varied at a frequency selected in accordance with traffic conditions in advance of the section, means for at times discontinuing the supply of said train governing code and for supplying the rails of said section with a detection code comprising

- periodically varied current having consecutive periodic variations of unequal duration, a code-following track relay for said section capable of following either of said two codes, and a train indicator for said section controlled by said track relay in such manner as to provide one indication when said track relay is following either of said two codes and to provide another indication when said track relay is shunted.
10. 5. In combination, a section of railway track normally supplied with a train governing code comprising rail current periodically varied at a frequency selected in accordance with traffic conditions in advance of the section, means for at times discontinuing the supply of said train governing code and for supplying the rails of said section with a detection code comprising periodically varied current having consecutive periodic variations of unequal duration, a code-following track relay for said section capable of following either of said two codes, a slow acting relay controlled by said track relay and capable of bridging the operation thereof when the track relay is following either of said two codes, and a train indicator for said section controlled by said slow acting relay.
6. In combination, a section of railway track normally supplied with a train governing code comprising rail current periodically varied at a frequency selected in accordance with traffic conditions in advance of the section, means for at times discontinuing the supply of said train governing code and for supplying the rails of said section with a detection code comprising periodically varied current having consecutive periodic variations of unequal duration, a code-following track relay for said section capable of following either of said two codes, a first slow acting relay controlled by said track relay and capable of bridging the operation of the track relay on alternate periodic variations of said two codes, and a second slow acting relay controlled by said track relay and said first slow acting relay and capable of bridging the operation of the track relay on alternate periodic variations of said two codes occurring between said first mentioned alternate periodic variations, and a train indicator for said section controlled by said second slow acting relay.
50. 7. In combination, a first and a second section of railway track, a first coding device for supplying said second section with a train governing code comprising rail current periodically varied at a given frequency, a first code-following track relay for said second section, a second coding device effective for supplying a detection code to said first section when said first track relay is shunted, said detection code comprising periodically varied rail current having consecutive periodic variations of unequal duration, means including a code-following contact of said first track relay for relaying said train governing code to the rails of said first section when said second section is unoccupied, a second code-following track relay for said first section capable of following either of said two codes, and a train indicator for said first section controlled by said second track relay in such manner as to assume a first condition when the second track relay is following either of said two codes and to assume a second condition when the second track relay is shunted.
70. 8. In combination, a stretch of railway track divided into an approach and a clearing section, means for supplying said clearing section with a train governing code comprising coded alternating current having substantially equal on and off periods, a first code-following track relay for said clearing section, means effective when said first track relay is following code for supplying said train governing code to the rails of said approach section, means effective when said first track relay is shunted for supplying said approach section with a detection code comprising coded alternating current having on and off periods of unequal duration, a second code following track relay for said approach section capable of following either of said two codes, a slow acting relay which becomes energized when said second track relay is following either of said two codes and which becomes deenergized when said second track relay is shunted, and a train indicator controlled by said slow acting relay.
9. In combination, a section of railway track normally supplied with a train governing code comprising coded alternating current having substantially equal on and off periods, means for at times discontinuing the supply of said train governing code and for supplying the rails of said section with a detection code comprising coded alternating current having on and off periods of unequal duration, train governing apparatus responsive to said train governing code but unresponsive to said detection code, a code-following track relay for said section, and a train indicator controlled by said track relay in such manner as to provide one indication when said track relay is following said train governing or said track clearing code and to provide another indication when said track relay is shunted.
10. In combination, a stretch of railway track intersected by a highway and comprising a signal approach section and a signal clearing section, a crossing signal for the intersection, means effective when said clearing section is unoccupied for supplying both said sections with a train governing code comprising coded alternating rail current having substantially equal on and off periods, coding means responsive to the entry of a train into said clearing section for supplying said approach section with a detection code comprising coded alternating rail current having on and off periods of unequal duration, train governing apparatus responsive to said train governing code but unresponsive to said detection code, means responsive to the entry of a train into said approach section for causing operation of said crossing signal, and means associated with said approach section and responsive to said train governing code and said detection code for clearing said crossing signal when the train clears said approach section.
11. In a coded wayside and cab signaling system for highway crossings on railroads in which a train governing code comprising coded alternating current having substantially equal on and off periods is normally supplied to the rails for governing wayside and cab signals, the combination with a signal at the crossing, of means for actuating said signal effective when a train enters the section approaching said signal, and means effective when the train clears the approach section for supplying a detection code to the rails of the approach section for clearing said signal, said detection code comprising coded alternating current having unequal on and off periods the relative time values of which are adjusted in such manner as to prevent response of the wayside and cab signals on said detection code.

12. In combination, two adjoining sections of railway track, means for supplying coded rail current to one of said sections, a code-following track relay for said one section, a decoding relay responsive to code operation of said track relay, and means including a contact of said track relay and a contact of said decoding relay for supplying rail current to the other of said two sections.
13. In combination, two adjoining sections of railway track, a source of coded current and a code-following track relay connected with the rails of one of said sections, a decoding relay responsive to code operation of said track relay, a slow acting relay controlled by said decoding relay, and means including a contact of said track relay and a contact of said slow acting relay for supplying rail current to the other of said two sections.
14. In combination, two adjoining sections of railway track, means for supplying one of said sections with rail current of a first or of a second code in accordance with traffic conditions, a code-following track relay for said one section, a decoding relay which becomes energized in response to operation of said track relay on either said first or said second code, means including a back contact of said decoding relay for supplying rail current of said first code to the other of said two sections, and means including a contact of said track relay for supplying rail current of said second code to said other section. 10 15
